UNITED STATES PATENT OFFICE.

SAMUEL ROBERT BELL, OF BEAUMONT, TEXAS.

ICE-MAKING APPARATUS.

1,049,197.

Specification of Letters Patent. Patented Dec. 31, 1912.

Application filed August 15, 1911. Serial No. 644,131.

To all whom it may concern:

Be it known that I, SAMUEL R. BELL, a citizen of the United States, and a resident of Beaumont, in the county of Jefferson 5 and State of Texas, have invented a new and Improved Ice-Making Apparatus, of which the following is a full, clear, and exact description.

My invention relates to ice making apparatus, and it has for its object to provide one having combined means for making the ice and for cooling the brine which is used in the ice making process, thereby dispensing with additional apparatus for cooling 15 the brine.

Additional objects of the invention will appear in the following complete specification, in which the preferred form of the invention is disclosed.

20 In the drawings similar characters of reference indicate corresponding parts in both the views in which—

Figure 1 is a perspective view partially in section showing my improved ice making apparatus; and Fig. 2 is a transverse sectional elevation of Fig. 1.

By referring to the drawings it will be seen that a large insulated tank 5 is provided, in which is disposed a plurality of expansion 30 tanks 6, these expansion tanks 6 having outer walls 7, and inner walls 8, which are spaced from each other, and which are held relatively to each other by pins 9. These expansion tanks 6 rest on blocks 10, disposed at the bottom of the tank 5. Within 35 the inner walls 8 of the expansion tanks 6, there are blocks 11, on which are supported water tanks 12, these water tanks 12 being spaced from the inner walls 8 of the expansion tanks. A pipe 13 leads 40 through an opening 14, in the end of the tank 5, this pipe 13 having branches 15, which connect with the interior of the expansion tanks 6, near their top. The branches 15 are commanded by valves 16.

45 A pipe 17 also extends through an opening 18 in the end of the tank 5, this pipe 17 being connected with depending branches 19, the said branches 19 being commanded by valves 20, and connecting with the interior 50 of the expansion tanks 6 near their bottom. Liquefied ammonia is supplied to the expansion tanks 6, by the pipe 17 and the branches 19, the ammonia, after it has been

expanded, being carried away by the 55 branches 15 in the pipes 13, so that it may be again liquefied in a manner well understood in the art. A pipe 21 is disposed in the tank 5, and near its inner side, branches 22 being connected with this pipe, which extend through the outer and inner walls 7 and 8 of the expansion tank 6, to the space between the inner wall 8 of the expansion tank and the wall of the water tank 12, these branches 22 being commanded by 60 valves 23. There is also a pipe 24, which extends around the tank 5 depending branches 25 being connected with this pipe 24, these branches 25 extending through the outer and inner walls 7 and 8 of the expansion tank 6, to communicate with the space between the inner wall 8 of the expansion tank and the wall of the water tank 12, near the bottom of the said water tanks. These depending branches 25 are commanded by valves 26. There are two pumps 27 having pipes 28 leading therefrom, these pipes 28 being in communication with the pipe 21. There are also pipes 29, which connect the pumps 27 with the pipe 24. 70 Leading from the pipes 29 there are depending branches 30, commanded by valves 31, these branches 30 communicating with the interior of the tank 5, near its bottom. The branches 32 which are in communication 75 with the pipes 28 communicate with the interior of the tank 5, near its top. The branches 32 are commanded by valves 33.

The branches 30 serve to afford communication between the brine pumps 27 through 90 the pipe 29 and the bottom of the large insulated tank 5, and the branches 32 serve to afford communication between the brine pumps and the top of the insulated tank 5, through the pipe 28.

95 It will be understood that the liquid ammonia is conveyed to the expansion tanks 6 between their outer and inner walls, where the ammonia expands, cooling the brine in the large outer tank 5, and also the brine 100 which is disposed between the inner walls 8 of the expansion tanks and the water tanks 12. The ammonia is then carried away back to the compressor, where it is again liquefied, to be again conveyed to the expansion 105 tanks. The brine within the tank 5, and also the brine disposed between the inner walls 8 of the expansion tanks and the walls

of the water tanks 12 is cooled by the vaporization of the ammonia, and after the plant has been in operation a short time it will be found that the brine when it enters the space between the inner walls 8 of the expansion tanks, and the walls of the water tanks 12, will be at such a low temperature that it will be unnecessary for the ammonia to reduce the temperature of the brine more than a few degrees, before the brine will be cold enough to freeze the water in the water tanks.

In my apparatus the ice is manufactured and the brine is cooled all in the same tank, which does away with a separate cooling tank for the brine, found in other apparatus. The brine is not only cooled in the space between the inner walls 8 of the expansion tank, and the wall of the water tank 12, but the brine circulates from the pipes 28 and 29, in communication with the pipes 21 and 24, through the pipes 30 and 32, to the large tank 5, where it is also cooled by the expansion tank. For this reason it is necessary to lower the temperature of the brine only a few degrees, when in the space between the inner walls 8 of the expansion tank, and the walls of the tank 12.

The brine in the large insulated tank 5 and outside of the expansion tank 6 may be used for refrigerating purposes, and after it has become cold it acts as an insulation for the expansion tanks 6. This brine in the large insulated tank 5, and outside of the expansion tanks has a tendency to support the freezing powers of the ammonia in the expansion tanks. The brine flowing through the pipe out of the large insulated tank 5 mixes with the warm brine flowing from between the expansion tank 6 and the tank 5, and prevents the working of the plant from becoming impaired by the heated brine.

Two brine pumps are provided for more complete circulation of the brine both between the inner wall 8 of the expansion tank 45 and the water tanks 12, and in the large outer tank 5. It will be understood that should one brine pump be damaged the apparatus may be used while repairs are being made.

Having thus described my invention, I claim as new, and desire to secure by Letters Patent:

1. In an ice making apparatus an expansion tank having side walls spaced apart one within the other, a water tank disposed within and spaced from the inner wall of the expansion tank, a third tank in which the expansion tank is disposed, and means for circulating brine in the third tank, and also between the water tank and the inner wall of the expansion tank.

2. In an ice making apparatus an expansion tank having side walls spaced apart, one within the other, a water tank disposed within and spaced from the inner wall of

the expansion tank, a third tank in which the expansion tank is disposed, and a conduit connecting the third tank with the opening between the water tank and the inner wall of the expansion tank.

3. In an ice making apparatus an expansion tank having side walls, spaced one with the other, a water tank disposed within and spaced from the inner wall of the expansion tank, a third tank in which the expansion tank is disposed, a pipe having two branches one opening into the space between the water tank and the inner wall of the expansion tank, and the other leading into the third tank, and a pump for forcing a fluid through the pipe.

4. In an ice making apparatus an expansion tank having side walls spaced apart, one within the other, a water tank disposed within and spaced from the inner wall of the expansion tank, a third tank in which the expansion tank is disposed, and a conduit connecting the third tank with the opening between the water tank and the inner wall of the expansion tank, and a pump for forcing a fluid through the conduit.

5. In an ice making apparatus an expansion tank having side walls spaced apart one within the other, a water tank disposed within and spaced from the inner wall of the expansion tank, a third tank in which the expansion tank is disposed, two pipes each having two branches one of the pipes on each of the branches communicating with the space between the water tank and the inner wall of the expansion tank, and the other branches communicating with the interior of the third-mentioned tank, and a pumping means for forcing a fluid through the pipes.

6. In an ice making apparatus an expansion tank having side walls spaced apart one within the other, a water tank disposed within and spaced from the inner walls of the expansion tank so that the said space will accommodate a limited supply of brine, an insulated tank in which the expansion tank is disposed for the accommodation of a relatively large supply of brine, and means for the circulation of the brine from the insulated tank to the space between the inner wall of the expansion tank and the wall of the water tank and back to the insulated tank so that the temperature of the brine need be lowered only a few degrees in the space between the inner wall of the expansion tank and the wall of the water tank.

7. In an ice making apparatus an expansion tank having side walls spaced apart one within the other, a water tank disposed within and spaced from the inner walls of the expansion tank so that the said space will accommodate a limited supply of brine, an insulated tank in which the expansion tank is disposed for the accommodation of

a relatively large supply of brine, a brine pipe having branches communicating with the top of the insulated tank and with the top of the space between the inner wall of the expansion tank and the wall of the water tank, a second pipe with branches communicating with the bottom of the insulated tank and with the bottom of the space between the inner wall of the expansion

sion tank and the water tank, and a pump 10 connected with the brine pipes.

In testimony whereof I have signed my name to this specification in the presence of two subscribing witnesses.
